UNITED STATES PATENT OFFICE.

LOUIS WILLIAMS, OF SEATTLE, WASHINGTON.

WALL RADIATOR.

Application filed March 20, 1926. Serial No. 98,160.

This invention in house heating systems pertains to a novel construction of radiator which is adapted to be associated with the wall or walls of a room to constitute a portion thereof.

The object of the invention, generally, is the provision of a radiator of this character which will occupy no greater space in a room than that taken up by the base board, 10 dado, or wainscoting of a wall.

A further object is to provide room-heating radiators which will radiate heat in a manner to preclude any stratum of cold air from occurring just above the plane of a 15 room floor, thereby heating the space within a room more economically and uniformly which renders the room more healthful and comfortable to its occupants.

Another object, and a very important one, 20 is to provide means to heat a room from all of its sides to preclude appreciable drafts or air currents.

With the above, and more specific objects and advantages in view, the nature of which 25 will appear in the following description, the invention consists in the novel construction, adaptation and combination of parts as hereinafter described and claimed; it being understood that changes in the form, 30 proportion, size and minor details of construction may be made within the scope of the claims without departing from the spirit of my invention.

In the accompanying drawings, in which 35 similar characters of reference indicate corresponding parts in all of the views,—

Figure 1 is a perspective view, showing portions of the walls of a room embodying my invention employed as a baseboard; Fig. 40 2 is a transverse vertical section taken substantially on line 2-2 of Fig. 1; Fig. 3 is a perspective view of one of the radiator members shown in Fig. 1; Fig. 4 is an inner face view of an end-plate or closure for a radiator member; Fig. 5 is an elevational view of a radiator comprising an assembly of vertically and horizontally connected members installed as a wainscot in the wall of a room. Fig. 6 is a transverse vertical sec- 45 50

is a longitudinal vertical section of a radiator member of the two-duct type shown in Fig. 3; Fig. 8 is a perspective view showing a one-duct radiator member. Fig. 9 is a perspective view of a partition-plug such as shown in Fig. 7.

Referring now, more particularly to the base board type of radiator, the same may be composed of one or more members to suit the specific form or length of wall. In Fig. 1 I show a single straight member 10, supplemented with a side 10¹ of an angle member to extend along the wall 11, as for example, between a door frame 12 and a wall corner 13; the complementary side 10² of the angle member extending between said corner and the door-frame 12¹ of the adjacent wall 11¹.

As shown, said members are provided with horizontal top and bottom walls 14, 15 and vertical front and back walls 16, 17, the upper front corner 18 being inclined preferably and formed to any desired configuration. In front of the top wall 14, a radiator member is provided with an upwardly directed ridge 19 extending from end to end of each member.

In the members now being considered there is provided in each a horizontal partition 20, see Figs. 2 and 7, extending the entire length of the respective member and at a corresponding elevation in associated or complementary members.

A partition 20 serves to divide the respective member into two tunnel-like compartments 21 and 22, hereinafter designated as ducts, having connective communication with each other by the provision of apertures 23 located in the partition in proximity to each end of the members. The purpose of 50 said apertures is to adapt the installation of the members to best suit the piping arrangement of the building whereby the heating medium (steam or hot-water) is supplied and withdrawn from a radiator, as will be presently explained.

Said apertures are desirably of a general circular form in plan with recesses, such as 24, Fig. 7, extending at diametrically opposite sides of an aperture. For closing cer-

tain of said apertures I provide cylindrical plugs 25 (Figs. 7 and 9) having a diameter to enter the apertures, each plug having a head 25¹ at one end to bear upon the top of 5 a partition, and horn elements 25² at its other end, which are adapted to pass through the respective recesses 24 to engage against cam elements 20¹ provided upon the under side of the partition. In proximity of each 10 end of a member, the same is provided in a wall thereof for each of its ducts with a screw threaded hole, indicated by 26, 26¹ and 27, 27¹ for the upper and lower ducts, respectively.

15 Where a room-wall is of greater length than the length of a single radiator member, a plurality of members are secured together in end-to-end relation making the ducts continuous for the entire length of a 20 radiator. The extremities of a series of members, or of a single member when used alone, are closed by means of detachable end plates 28. As illustrated, said members are provided near their extremities with apertured lugs 29; similar lugs 29¹ being provided upon the end plates 28, to receive coupling bolts 30 whereby the members and end plates are secured together.

To prevent leakage at the joints, gaskets 30 or other suitable seam closing means, such as a gasket, denoted by 31, in Fig. 7, is employed in grooves 32 and 33 (Figs. 3 and 4) provided in the opposing surfaces of the radiator members and end plates.

35 A radiator of the "base-board" type above described is installed by inserting the same into the room wall so that the inner side of the ridge 19 will be in a plane with the wall's plaster surface 34. To effect such an arrangement, the wall stud elements, as 35, Fig. 2, may have to be recessed, as at 36, to receive the rear portion of a radiator member.

As also shown in Fig. 2, a radiator member 45 is superposed upon the rough flooring 37, the upper or wearing floor 38, being laid in front of the radiator, although the radiator may be arranged otherwise; for instance, entirely above the upper flooring 38. Excepting 50 the front and corner surfaces 16 and 18, respectively, the radiator members are embedded in the room wall; and the surfaces within the wall being desirably covered or coated with a suitable heat insulating material 39.

40 represents a strip of wood or moulding to make, if desired, a dust-proof closure between the flooring 38 and the radiator. The manner of installing the "base-board" radiator above described, is to unite the adjoining radiator members and end plates 28 by means of bolts 30 passing through the respective lugs 29 and 29¹.

With two-duct radiator members, all of 65 the apertures 23 in the partition 20 are

closed by plugs 25 except the aperture nearest one of the end plates 28 which remains open for the heating medium to pass, as denoted by arrow A, from one of the ducts 21 into the other duct 22.

70 Screw threaded plugs 41, of known construction, are employed to close all of the holes 26, 27 excepting those indicated by 26¹, 27¹ most remote from the partition-aperture which is left open in each duct.

75 In the hole 26¹, see Fig. 2, is engaged a pipe nipple 42 which is connected by means of pipe elements 44 and suitable fittings such, for example, as elbows 45 and a union 46, with a service pipe 47 leading from a 80 hot-water or steam-generating boiler, not shown. In the hole 27¹ is engaged a nipple 48 which is likewise connected by suitable pipe elements and fittings with a return service pipe 49 leading back to the boiler above 85 mentioned.

In practice, a controlling valve such as 50 is included in one of the pipe connections, preferably in the supply, and is located in a casing 51 having a door 52 which may be 90 swung open to give access to the valve for regulating the supply of the heating medium to a radiator.

95 As shown all of the pipe connections and the containing casing 51 for the valve 50 are positioned within the wall or walls of a room.

100 Instead of using two-duct members, a "base-board" radiator may be formed with single duct members one of which is shown in Fig. 8. This member denoted by 10³ has its inlet and outlet holes 26² and 27², respectively, disposed at different elevations at opposite ends of the member. Where two or more of this style of members are utilized in 105 the construction of a radiator, only the end-most holes are left open for the pipe connections.

110 In Figs. 5 and 6, I illustrate my invention as applied to what I term a "wainscot" 110 radiator, which is built into a wall as represented in the referred to views. In this application—wainscot—a multiplicity of superposed horizontal ducts are employed which, in the illustrated embodiment is composed of 115 a plurality of members 10^a, 10^b and 10^c, each having, preferably, two ducts 21¹ and 22¹. The upper tier of members 10^a being connected at 26³ with the supply connection 42¹ and the lower tier of members 10^c being 120 connected at 27³ with the return connection 48¹.

125 Similarly to the arrangement as described with reference to the two-duct "base-board" radiator, connection is had between the ducts 21¹—22¹ in each tier of members by means of apertures 23¹ in the respective partitions 20¹ as indicated by dotted lines in Fig. 5. At or near the opposite ends of the respective 130 tiers of members the same are communica-

tively connected with each other by means of nipples 55. The direction arrows A¹ in Figs. 5 and 6, represent the flow of the heating fluid with respect to the several radiator members. The lower or base course of members 10^c is provided with an upwardly directed ridge 19 at the top thereof; the top and intermediate courses of members 10^a and 10^b are provided with ridges 19 and 19¹ at their tops and bottoms, respectively; the top ridge 19 of the upper course, 10^a, serving as a wall to receive the plaster of the room wall therebehind, while the other ridge 19¹ of this top course and the ridges of subjacent courses serve to close the openings between the several courses at the front of the radiator.

The construction and manner of installing and using radiators embodying the present invention will, it is believed, be understood from the foregoing description.

What I claim, is,—

1. In a heating system, a radiator adapted to be employed in a recess of the wall of a room, said radiator comprising horizontally aligned tubular open-ended members and end closure plates, and external means for uniting said members and plates adapted to be concealed in the recess of the room wall, said members being provided at the front of the respective top walls thereof with an upwardly directed ridge, said members being further provided at the back with means for connecting the same with a circuit for a fluid heating medium.

2. In a heating system, a radiator adapted to be built into the wall of a room of a building, said radiator comprising a plurality of communicatively connected tubular open-ended members having partitions dividing the interiors of the respective members into upper and lower ducts, said partitions being provided with horizontally spaced apart apertures affording communication between the ducts of each member, means to close said apertures selectively, means to close the outermost ends of the members when assembled as a radiator, and means for supplying and withdrawing a fluid heating medium to and from the respective ducts of the radiator through the back of the latter.

3. A radiator adapted to be located in the recess of the wall of a building and having a front wall adapted to constitute a continuation of the building wall, said radiator being composed of flat tubular open-ended sections disposed in end to end relation, ears adapted to be concealed in the recess of the building wall and externally located on the ends of the top and bottom walls of said sections, closure plates for the ends of the sections at the ends of the radiator, bolts extending through the ears at adjacent ends of the sections to secure the latter together, and

bolts extending through the closure plates and the ears on the adjacent ends of the sections for securing the closure plates in place.

4. A radiator adapted to be located in the recess of the wall of a building and having a front wall adapted to constitute a continuation of the building wall, said radiator being composed of flat tubular open-ended sections disposed in end to end relation, ears adapted to be concealed in the recess of the building wall and externally located on the ends of the top and bottom walls of said sections, closure plates for the ends of the sections at the ends of the radiator, bolts extending through the ears at adjacent ends of the sections to secure the latter together, and bolts extending through the closure plates and the ears of the adjacent ends of the sections for securing the closure plates in place, said sections having longitudinal positioning flanges at the tops thereof in front of the ears.

5. A radiator adapted to be located in the recess of the wall of a building and having a front wall adapted to constitute a continuation of the building wall, said radiator being composed of flat tubular open-ended sections disposed in end to end relation, ears adapted to be concealed in the recess of the building wall and externally located on the ends of the top and bottom walls of said sections, closure plates for the ends of the sections at the ends of the radiator, bolts extending through the ears at adjacent ends of the sections to secure the latter together, bolts extending through the closure plates and the ears on the adjacent ends of the sections for securing the closure plates in place, and mating gasket-receiving grooves in the end edges of the walls of the sections and in the inner faces of the closure plates.

6. In a radiator of the type described, a flat tubular open ended radiator section divided by a horizontal partition into upper and lower ducts, said partition having an opening therein near each end capable of affording communication between the ducts when open, removable closures for said partition openings, the rear wall of the radiator section having a pair of openings at each end entering the respective ducts whereby supply and outlet pipes may be connected to either end of the casing, and removable closures for desired ones of the latter openings.

7. In a radiator of the type described, a flat tubular open ended radiator section divided by a horizontal partition into upper and lower ducts, said partition having an opening therein near each end capable of affording communication between the ducts when open, removable closures for said partition openings, the rear wall of the radiator

section having a pair of openings at each end entering the respective ducts whereby supply and outlet pipes may be connected to either end of the casing, and removable closures for desired ones of the latter openings, said radiator section having external ears on the ends of the top and bottom walls thereto to facilitate bolting of a plurality of the sections together in end to end relation and bolting of closure plates to free ends of the sections.

Signed at Seattle, Washington, this 17th day of February, 1926.

LOUIS WILLIAMS.
